[57] CLAIM

The ornamental design for a clamping strip for shower curtain, substantially as shown and described.

DESCRIPTION

FIGS. 1 and 2 are fragmentary top perspective views of the upper end portion of a clamping strip for shower curtain showing my new design;

FIG. 3 is an end elevation view thereof;

FIG. 4 is a fragmentary front elevation view of the upper end portion thereof;

FIG. 5 is a fragmentary side elevation view of the upper end portion thereof taken from the left of FIG. 4;

FIG. 6 is a fragmentary side elevation view of the upper end portion thereof taken from the right of FIG. 4;

FIG. 7 is a fragmentary rear elevation view of the upper end portion thereof; and

FIGS. 8 and 9 are top perspective views, respectively, showing the clamping strip installed against a fragmentary end wall and tub rim elements, which are shown in broken lines for illustrative purposes only and form no part of the claimed design. The showing of broken away elements in the views is indicative of indeterminate length.
